(57) **CLAIM**

The ornamental design for a geometric hanging basket, substantially, as shown and described.

DESCRIPTION

FIG. 1 is a front elevational view of a geometric hanging basket showing my new design;

FIG. 2 is a right side elevational view thereof, the left side elevational view being a mirror image thereof;

FIG. 3 is a rear elevational view thereof;

FIG. 4 is a top plan view thereof;

FIG. 5 is a cross-sectional view thereof, taken along line 5—5 of FIG. 2;

FIG. 6 is a cross-sectional view thereof, taken along line 6—6 of FIG. 3; and,

FIG. 7 is a bottom plan view thereof.
